UNITED STATES PATENT OFFICE.

WILLIAM JOHN HUBERT DIPLOCK, OF CROYDON, ENGLAND, ASSIGNOR OF ONE-HALF TO ERITH'S ENGINEERING COMPANY, LIMITED, OF KINGSWAY, ENGLAND, A BRITISH COMPANY.

UNDERFEED MECHANICAL STOKER.

Application filed May 5, 1924. Serial No. 711,163.

To all whom it may concern:

Be it known that I, WILLIAM JOHN HUBERT DIPLOCK, a subject of the King of Great Britain, residing at Ingleside, Barnclay Road, Croydon, in the county of Surrey, England, have invented certain new and useful Improvements in or Relating to Underfeed Mechanical Stokers, of which the following is a specification.

10 This invention relates to mechanical stokers for boiler and other furnaces, and refers more particularly to multiple retort underfeed stokers of the kind in which the fuel is fed into a plurality of troughs or retorts by means of reciprocating rams, and in which tuyères or other air emission means are provided for the admission of forced draught air into the fuel as it rises from the retorts and spreads over the tops of the 20 tuyères.

In multiple retort stokers of this character the several troughs or retorts are arranged above a main air supply chamber to which full pressure air, under the control of 25 a single damper, is delivered by a fan, and overfeed or extension grates are usually provided at the rear ends of the retorts, through which a supplementary supply of air under control and at reduced pressure is admitted 30 to the fuel so that the final stages of combustion are completed upon the extension grates before the fuel is discharged, either automatically or otherwise, over dump plates or other similarly acting devices, to 35 the ashpit.

It has been found in practice that combustion tends to proceed more rapidly at some than at other parts of the fuel bed, this uneven combustion being principally 40 due to the fact that the thickness of the fuel bed varies from time to time over different parts of the stoker, and the air admitted through the tuyères or other air emission means tends to take the line of least 45 resistance and accordingly to provide an excess of air to the thinnest part of the fuel bed and an insufficient supply to the thickest parts and it is the chief object of the present 50 invention to promote even combustion over the entire fuel bed.

According to one feature of the present invention the main air chamber is divided up by means of partition walls into smaller chambers, each chamber being provided with

a damper by means of which the volume of air supplied thereto from the main air duct or from a common air chamber in communication therewith, can be regulated as desired. If, therefore, combustion should take place at a more rapid rate in any particular zone 55 of the furnace than in others, or, if any zone is not receiving an adequate supply of air or is receiving an excess of air, an even rate of combustion throughout the entire fuel bed can be produced by suitably adjusting 60 one or more of the dampers leading to the several air chambers, and thereby increasing or reducing the volume or pressure of the air supplied to the tuyères or other air emission means which are in communication 65 with the said chamber or chambers.

According to a further feature of the present invention, a partition is provided in the main air chamber to divide the same into a pair of compartments, and a damper is 70 hinged to the upper portion of this partition to be movable to inclined positions in order to direct air from the front compartment directly to the fuel bed above the next succeeding compartment. In some instances, it 75 is desirable to provide a supplementary air member beneath the extension grate, and when this is done a damper may be provided therefor and may be located at substantially 80 the same level as the damper in the partition wall just referred to, whereby the air may have a direct course from the front compartment to the supplementary chamber beneath the extension grate. The aforesaid 85 improvements may be applied to stokers provided with variable stroke pushers located within the retorts with or without moving retort side walls for the purpose of advancing and slicing the fuel or to stokers provided with agitating devices and with or 90 without supplementary air emission means.

In order that the invention may be understood and readily carried into effect, the same will now be explained more fully in connection with the accompanying drawings, in which,

Figure 1 is a diagrammatic longitudinal section of a stoker showing the invention applied thereto, and

Figure 2 is a transverse section of the 105 same, taken on the line 4—4 of Figure 1.

Referring to the drawings, the invention is shown applied more or less diagrammat-

ically to a multiple retort underfeed stoker, the fuel feeding ram apparatus being designated in its entirety by the letter F. G is the air duct leading from a source of air supply in the form of a pressure fan or blower, not shown. An air chamber is arranged beneath the retorts M and tuyères N, in the present instance, and is divided by a transversely disposed vertical partition H into a front compartment G¹ and a rear compartment G². Air from the duct G is admitted at the desired pressure through a damper I to the compartment G¹, and part of it passes from the compartment G¹ at the desired pressure through a damper H¹ to the compartment G². J and J¹ are convenient arrangements of links and levers by which the dampers I and H¹ can be adjusted as required.

20 It will be noted that the partition H is disposed adjacent the forward end of the main air chamber and substantially under that portion of the retorts where the fuel bed is usually thicker and humps up due to the fuel feeding mechanism.

It will be obvious that, as shown diagrammatically by the dotted lines in Figure 1, the fuel as it is fed into the stoker humps up and is thicker at the front portion of the fuel bed, above the compartment G¹, so that in order to penetrate the increased thickness of the fuel at this point and promote perfect combustion, air should be supplied at a greater pressure than is required at the lower points of the fuel bed above the compartment G² where the fuel bed is thinner. Such adjustment as will be required can be readily effected by the arrangement above described.

40 As is the usual practice in stokers, a supplementary air chamber or compartment K¹ is provided beneath the extension grates K², and a damper K is provided for regulating the amount of air entering this supplementary chamber. This damper K is shown as being arranged at substantially the same level as the damper H¹, so that when both of these dampers are open, the current of air from the front compartment G¹ will pass more or less directly to the chamber K¹.

It will be obvious that instead of a single transverse partition H two or more partitions disposed at suitable distances apart and provided with dampers, may be provided so as to further control the supply of air admitted at different points to the fuel bed; while the air instead of passing successively through the several chambers can, if desired, be conducted from the source of air

supply through a longitudinally disposed duct to each of such other chambers.

In lieu of a single damper H¹, as shown, two or more dampers may also be employed, while in order to direct the air upwardly into the compartment G¹, a curved deflector plate L may be provided at the base of this air compartment. Shoots, riddling hoppers or other suitable means, not shown, having exit openings may be provided to facilitate the removal of any riddlings which may collect at the base of the compartments G¹ and G².

What I claim and desire to secure by Letters Patent of the United States is:—

1. An underfeed stoker comprising an underfeed retort, an air chamber beneath said retort, tuyères located at the sides of said retort for admitting air into the fuel as it rises from the retort, a partition wall extending transversely of said chamber and located beneath the forward end of said retort beneath the thickest portion of the fuel bed for dividing the chamber into front and rear compartments, and a damper in said partition wall adjacent the top thereof and movable to deflecting positions to direct air from the front compartment directly to the fuel bed above the rear compartment.

2. An underfeed stoker comprising an underfeed retort, an air chamber beneath said retort, tuyères located at the sides of said retort, a partition wall extending transversely in the chamber and arranged beneath the forward end of the retort where the fuel bed is thickest for dividing the chamber into two compartments, and a damper hinged at its lower edge to the upper portion of said partition, said damper being movable to inclined positions to direct air from the front compartment directly to the fuel bed above the compartment beyond the partition.

3. An underfeed stoker comprising an underfeed retort, an extension grate at the rear end of said retort, a main air chamber beneath said retort, a supplementary air chamber beneath said extension grate, tuyères located at the sides of said retort for admitting air into the fuel as it rises from the retort, a partition wall extending transversely of said main air chamber and dividing the same into two compartments, a damper hinged at its lower edge adjacent the top of said partition wall, and a second damper for the supplementary air chamber arranged at substantially the same level as said first damper.

WILLIAM JOHN HUBERT DIPLOCK.
